(57) **CLAIM**

The ornamental design for an animal deterrent spike, as shown and described.

DESCRIPTION

FIG. 1 is a perspective view of the animal deterrent spike showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is another perspective view thereof; and,

FIG. 9 is another perspective view shown in an alternate configuration thereof.

The broken lines throughout the drawing figures depict portions of the animal deterrent spike that form no part of the claimed design.
